UNITED STATES PATENT OFFICE.

MERVYN LA FAYETTE STANSBURY, OF HIGHWOOD, NEW JERSEY.

GARMENT-HANGER.

No. 828,435.

Specification of Letters Patent.

Patented Aug. 14, 1906.

Application filed May 22, 1905. Serial No. 261,606.

To all whom it may concern:

Be it known that I, MERVYN LA FAYETTE STANSBURY, a citizen of the United States, residing at Highwood, in the county of Bergen and State of New Jersey, have invented 5 certain new and useful Improvements in Garment-Hangers, of which the following is a specification.

My invention relates to garment-hangers, 10 and more particularly to such constructions of this character as are ordinarily termed "closet sets," designed to be fastened upon the inside of a closet-door and to support trousers, skirts, or coats.

15 The object of the invention is to provide such a hanger which shall admit of an economy of space in hanging garments, which shall permit easy removal or replacement of a garment, which shall provide for the hanging of a double row of trousers, and therefore double the capacity of the closet.

20 Heretofore the so-called "closet sets" designed to be supported on a closet-door have only provided for the hanging of one line of 25 trousers or skirts and have made no provision for the hanging of coats, hats, &c.

25 My device allows the hanging of two rows of trousers with intermediate supports for coats, &c., and provides a support for hats 30 and neckties as well. It is designed to be fastened to the inside of a closet-door and to project inward into the closet-space. Thus when the door is closed the heretofore wasted 35 space in the center is occupied.

35 My invention consists in the peculiar constructions and arrangements of parts set forth in the appended claims.

40 In the drawings, Figure 1 is a perspective view of one form of my hanger. Fig. 2 is a side view. Fig. 3 is a front view of a construction embodying the principles of my hanger, but showing a different form of support. Figs. 4 and 5 are details of modifications.

45 Like numerals designate like parts.

40 In Fig. 1, 2 designates a base-plate from which projects a supporting bracket or bar 3 of any convenient length and cross-section.

50 Projecting outwardly on both sides of the bar 3 are a row of trousers-hanger rods 4. These are preferably given an upward slant on an angle corresponding to the angle of the bottom edge of a trousers-leg, and the distance between the rods is just sufficient to 55 allow the insertion of a pair of trousers-legs between any two of them. In Fig. 1 I have

shown the rods 4 as arranged in couples for the sake of not obscuring the coat-hangers; but it will be understood that preferably the pins are set side by side at equal space apart 60 in the manner shown in Fig. 4. This arrangement permits the accommodation of a much greater number of trousers than when they are arranged in couples.

65 The rods 4 are slightly resilient, and it is an easy matter to insert a pair of trousers between them or to withdraw the same. There are no clamps to open nor any projecting parts which are liable to catch and tear the cloth when the trousers are hastily removed. In addition to this two smooth rounded parallel rods, between which the trousers are placed, permit them to be inserted some distance above the knee and then drawn down to the position shown in 75 Fig. 3, between the rods 4", thus smoothing out and creasing the trousers.

70 If desired, the rods 4 or 4" might be mounted so as to rotate as rollers or each be formed with a surrounding revoluble sleeve 4', as 80 shown in Fig. 5.

85 The under side of the bracket or supporting-bar 3 is provided with means for supporting a row of coat-hangers 5. In Figs. 1 and 2 this means is shown as series of openings through the longitudinal rib 3', into which the hooks are placed; but a slightly more 90 convenient arrangement is shown in Fig. 4, where the bar 3 carries beneath it a longitudinal rod 3", over which the hooks of the 95 coat-hangers may be caught. If the form shown in Fig. 1 is used, the holes 3" should be placed between the couples of trousers-hanger rods. If that shown in Fig. 4 be used, the coats or other garments may be 100 shifted on the rod to the most convenient position.

105 At the inner end of the bar 3 I place a belt or cravat saddle 6. This has a rounded upper face and a flange 6' at the front to prevent the cravats, belts, braces, or whatever is hung over the saddle from slipping off.

110 77 designate a series of vertical pegs projecting upward from the bar 3 and intended for the support of hats.

115 In Fig. 3 I show the bar 3 as supported on standards 8. This form is of great convenience in tailoring-shops.

120 The advantages of my invention over anything known to me are many. When in place on a closet-door and filled with clothes, space in the interior of the closet ordinarily

unused is filled, and yet when the door is opened the closet is entirely unobstructed. It doubles the number of garments which may be hung from the same length of supporting-bar. It combines in one compact construction means for hanging trousers, coats, hats, and belts, so arranged that any garment thereon may be easily handled without the necessity of removing or shifting any other garment.

The construction shown in Fig. 3 is of especial utility in clothing establishments. In these it is the common practice to pile the clothes on counters. This entails when a certain coat or pair of trousers is desired either the hauling out of the garment from the middle of the pile, which is liable to crease or rumple the remaining clothes, or else that the superincumbent layers of garments should be removed—a matter of some difficulty and liable to disorder the pile of clothes. By my construction clothes may be inspected or handled and are always kept in good shape.

While I have shown in Figs. 1, 2, and 5 the rods 4 as separate pieces inserted from each side of the central support 3, I believe the preferable manner of forming these rods 4" would be as shown in Fig. 3, where opposite rods are of one continuous piece inserted through the bar. These may be either bent upwardly before insertion or after and may be of any cross-sectional form desired.

Having described my invention, what I claim is—

1. In a garment-hanger, a central longitudinal supporting-bar, rods projecting outward therefrom on opposite sides thereof, adjacent rods on the same side being so placed as to hold a pair of folded trousers-legs or other garment between them, and spreaders or hangers hung on the central support beneath the said bar, substantially as described.
2. In a garment-hanger, a central longitudinal supporting-bar, a series of adjacent rods projecting outward therefrom on both sides, so relatively positioned to each other

that adjacent rods on the same side will hold a pair of trousers-legs between them; a longitudinal bar supported beneath the main bar, and coat-hangers hung upon said bar, substantially as described.

3. In a garment-hanger, a central longitudinal supporting-bar, vertical pegs on the supporting-bar, oppositely-placed trousers-holding rods projecting outward therefrom on opposite sides, adjacent rods on the same side being so relatively positioned as to hold a pair of folded trousers-legs or other garments between them, and coat-hangers supported on the said bar beneath the same, substantially as described.

4. In a garment-hanger, a central longitudinal supporting-bar, vertical pegs on the supporting-bar, oppositely-placed rods projecting outward therefrom on opposite sides, adjacent rods on the same side being so relatively positioned as to hold a pair of folded trousers-legs or other garments between them, and coat-hangers supported on the said bar beneath the same, and a belt or cravat saddle on said support, substantially as described.

5. In a garment-hanger, a central longitudinal supporting-bar having a base for attachment to a vertical surface, rods projecting outward therefrom on opposite sides thereof adjacent rods on the same side being so relatively positioned as to hold a pair of folded trousers-legs or other garments between them, vertical hat-pegs on the upper side of the supporting-bar, means for supporting coat-hangers from the said longitudinal bar beneath the trousers-rods, and a cravat-saddle at the junction of the longitudinal bar with the base, substantially as described.

In testimony whereof I have signed my name to this specification in the presence of two subscribing witnesses.

MERVYN LA FAYETTE STANSBURY.
